sionsmechanik, Berne, Switzerland, a corpora-
tion of Switzerland

Application March 24, 1939, Serial No. 264,046
In Switzerland March 31, 1938

7 Claims. (Cl. 74—1)

The invention relates to a follow-up mechanism in an indicating device particularly in a device for indicating and recording the charging pressure of an internal combustion engine in relation to the tachometer.

According to the invention a flexible diaphragm or composite diaphragm is exposed to the fluid pressure to be recorded and moves a member in the path of an oscillating driver actuating the recording mechanism, so that the travel of the driver, in one direction, is variably limited by the said moving member. The action of the recording mechanism is, consequently, dependent on the fluid pressure, but that pressure is not used for actuating the recording mechanism.

An example of apparatus according to the invention is shown in the accompanying drawing, in which

Fig. 1 is a vertical section thereof, partly broken away, and

Fig. 2 is a perspective view of the follow-up mechanism.

The casing 1 shown in the left hand side of Fig. 1, partly broken away is divided by a horizontal partition 2 into two chambers 3 and 4. The upper chamber 4 contains the recording device, which may be of any convenient construction, and of which only the record sheet 5 is shown. Mechanism for actuating the recording implement is contained in the chamber 3. The record sheet 5 may be moved at a constant speed, e. g. by means of a clockwork, or at a speed varying with that of a driving shaft, e. g. the axle of a vehicle, according to the purpose for which the instrument is used.

Joined to the casing 1 is a cylindrical casing 6. The dividing wall between the casings has an opening 23 with a circular cover 7 on one side and a cover 22 on the other side, and opposite this opening the casing 6 has an opening with a gas-tight cover 8, held in position by a screw ring 9. The cover 8 has an inwardly directed recess, and outside it there is an external cover 10 with an outwardly directed recess forming a compartment 11, in which there are two bevel gears 12, 13 for driving spur gears 14, 15 in the cavity in the cover 8. A nipple 16 is screwed into the upper part of the cover 10, and projects through the cover 8. This nipple serves for joining the pressure pipe to the instrument. This may, for example, be a pipe connected to the induction pipe of an internal combustion engine. The pocket 11 has a tubular extension 10^a with a gland 17 therein for a shaft 18 car-

rying the gear 12. The shaft has a gudgeon 19 for coupling therewith a driving shaft, which may for example be driven by the axle of a vehicle. The gears 13 and 14 are fixed to a shaft 20 passing through a hollow shaft 21 between the covers 7 and 8. Between the covers 7 and 22 this shaft drives the actuating mechanism of a speedometer, not shown in the drawing.

The gear wheel 15 is fixed to a shaft 25, which carries inside the casing 6 a disk 26, which carries a cam roller 27. Supported by a bar 28 in the casing 6 are two elastic diaphragm boxes 29, but there may be more than two such boxes. A link 30 connects the bottom of the lower box to an arm 31 on a shaft 32 mounted in bearings in the covers 7 and 8, and to this shaft is fixed also a curved arm 33 having a finely serrated convex edge. A detector lever 34 mounted on sleeve 52 on shaft 38 has a laterally projecting tooth 35 in the path of the curved arm 33 and a lever 37 also mounted on sleeve 50 is held by a spring 36 in contact with the roller 27, so that at intervals the detector lever 34 is removed from contact with the curved arm 33, and the tooth 35 is disengaged from the serrated edge of that arm, which is thus enabled to assume a new position if the fluid pressure has changed.

The shaft 38 parallel to shaft 25 has a toothed quadrant 39 fixed thereto, and a coiled spring 40 acts on this quadrant so that when the quadrant is released from a detent to be described hereinafter it is rotated till an abutment 41 projecting laterally therefrom strikes an abutment 34^a on the detector lever 34. The position of the quadrant at this time consequently depends on the pressure which has been acting on the diaphragm boxes during the preceding interval of time.

The quadrant is locked in the position to which it is moved by the spring, there being for this purpose a lever 42 having a plurality of teeth, held by a spring 43 in engagement with a toothed wheel 44 fixed to a pinion 45 in mesh with the quadrant 39. The teeth of the wheel 44 and the detent lever 42 are of such configuration that the detent lever restrains the wheel from rotating in one direction only. The lever 42 is connected with a lever arm 46 resting on a cam 47 rotating with the disc 26. When the lever is lifted by the cam 47 the lever 42 releases the wheel 44 and quadrant 39. The shaft 38 has fixed thereto a quadrant 48 for actuating, by means of gears 49, 49^a, a vertically reciprocatable rack 50 having at its upper end

the style (not shown) which records the fluid pressure or degree of vacuum on the sheet 5.

At each revolution of the disc 26 the detector lever 34 is disengaged from the curved arm 33, which is thus able to assume a new position, whereupon the lever 34 returns into engagement therewith. The cam 47 and lever 46 then disengage the lever 42 from the wheel 44 and release the quadrant 39, which assumes a position depending on that taken by the detector lever 34, so that if there has been a change of pressure the style is moved.

It will be clear that in either case the motive power for moving the style is derived from the spring 40, so that the friction incidental to the movement of that style is overcome by the spring alone and does not in any way react on the setting of the mechanism actuated by the fluid pressure.

The instrument described may with advantage be used in connection with aircraft, for the purpose of obtaining a continuous record of charging pressure or fuel consumption concurrent with a record of speed.

What I claim as my invention and desire to secure by Letters Patent of the United States is:

1. A follow-up mechanism comprising an elastic diaphragm device responsive to fluid pressure, an oscillating detector, a rotatable driving element for said detector, an abutment adjusted by said diaphragm device in the path of said detector limiting the movement of said detector in one direction, style actuating mechanism for recording the fluid pressure and an oscillating driver actuated by said driving element for actuating said style actuating mechanism, said detector limiting the movement of said driver in one direction.

2. A follow-up mechanism as set forth in claim 1 in which said abutment comprises an arm on a shaft rotatable by said diaphragm device.

3. A follow-up mechanism as set forth in claim 1 in which said diaphragm device comprises a series of elastic-walled boxes and a chamber containing said boxes.

4. A follow-up mechanism as set forth in claim 1 in which said abutment comprises a curved arm on a shaft rotatable by said diaphragm device and said detector comprises a lever carrying an abutment in the path of a quadrant which is intermittently released and is then moved by a spring against said abutment thereby actuating said style actuating mechanism.

5. A follow-up mechanism as set forth in claim 1 in which said abutment comprises a curved

arm on a shaft rotatable by said diaphragm device and said detector comprises a lever carrying an abutment in the path of a quadrant which is intermittently released and is then moved by a spring against said abutment thereby actuating said style actuating mechanism, said quadrant being locked by a ratchet device which is put out of action by a lever when said detector engages said first-named abutment.

10. A follow-up mechanism comprising an elastic diaphragm device responsive to fluid pressure, an oscillating detector, a rotatable driving element for said detector, an abutment adjusted by said diaphragm device in the path of said detector

15. limiting the movement of said detector in one direction, style actuating mechanism for recording the fluid pressure, an oscillating driver actuated by said driving element for actuating said style actuated mechanism, said detector limiting the movement of said driver in one direction, said adjustable abutment being a curved arm on a shaft rotatable by said dia-

20. phragm device, a quadrant, said detector being a lever carrying an abutment in the path of said quadrant which is intermittently released and then actuated by a spring up to said abutment

25. thereby actuating said style actuating mechanism, said quadrant being locked by a ratchet device which is disabled when said detector engages said first-mentioned adjustable abut-

30. ment.

7. A follow-up mechanism comprising an elastic diaphragm device responsive to fluid pres-

35. sure, an oscillating detector, a rotatable driving element for said detector, an abutment adjusted by said diaphragm device in the path of said detector limiting the movement of said detector in one direction, style actuating mechanism for

40. recording the fluid pressure, an oscillating driver actuated by said driving element for actuating said style actuated mechanism, said detector limiting the movement of said driver in one direction, said adjustable abutment comprising a shaft rotatable by said diaphragm device

45. and a curved arm thereon, a quadrant, said de-

50. tector comprising a lever carrying an abutment in the path of said quadrant which is inter- mittently released and it is then moved by a spring up to said abutment thereby actuating said style actuating mechanism, a ratchet de-

vice for locking said quadrant and a lever for

disabling said ratchet device when said detector engages said first-mentioned adjustable abut-

ment.

ERNST BAUMANN.
